United States Patent Office.

BYRON CLARK SMITH, OF AUBURN, NEW YORK, ASSIGNOR TO HAYDEN & LETCHWORTH.

Design No. 3,711, dated October 12, 1869.

DESIGN FOR A TRADE-MARK.

The Schedule referred to in these Letters Patent and making part of the same.

To all whom it may concern:

Be it known that I, BYRON CLARK SMITH, of Auburn, in the county of Cayuga, and State of New York, have invented a Design for a Trade-Mark; and I do hereby declare that the following, taken in connection with the drawings which accompany and form part of this specification, is a description of my invention sufficient to enable those skilled in the art to practise it.

My design consists of a stamp, or of a card, or label, to be in any convenient way made in or affixed upon articles of manufacture, the same being as follows:

The outline or enclosure is of curved form, as shown, and within the enclosure, about at its centre, is a star, with the word "warranted" within it. At one side of the star, the words "star-wheel" and "Norway iron," and at the other side, the word "pattern," a blank space preceding this word "pattern," being intended

to be filled up with the word "Cincinnati," "Auburn," or any other word, to indicate the particular pattern of wheel to be designated. Beneath the star are the words or abbreviations "in. diam.," and at either side of said abbreviations, the further abbreviations "in. iron," and "in. axle."

I intend this design as a stamp, label, or brand, and more especially in connection with the manufacture and sale of "fifth-wheels," so called, in vehicles or carriages.

I claim, as my invention, the design for a trademark, as described and shown.

Dated September 13, 1869.

BYRON C. SMITH.
